UNITED STATES PATENT OFFICE.

FRANK D. HOLMES, OF DETROIT, MICHIGAN, ASSIGNOR TO DETROIT ALASKA KNITTING MILLS, OF DETROIT, MICHIGAN, A CORPORATION OF MICHIGAN.

KNITTING-MACHINE.

1,081,043.

Specification of Letters Patent.

Patented Dec. 9, 1913.

Application filed June 19, 1913. Serial No. 774,499.

To all whom it may concern:

Be it known that I, FRANK D. HOLMES, a citizen of the United States, and a resident of Detroit, in the county of Wayne and 5 State of Michigan, have invented a new and Improved Knitting-Machine, of which the following is a specification.

This invention relates to mechanism for forming loops from one of two yarns employed in the knitting of hosiery and similar tubular goods, and its object is to provide a self-adjusting, eccentrically mounted, freely rotary, and vertically slidable disk having radially projecting looping points 15 over which one of the two yarns can be looped during the knitting operation.

In the accompanying drawings, Figure 1 is a plan of this mechanism, and Fig. 2 is a section on the line 2—2 of Fig. 1.

20 Similar reference characters refer to like parts in both views.

As this is merely an attachment adapted to be mounted on machines now in general use, the driving mechanism need not be explained, excepting that a proper gear may engage the teeth 3 of the cam-cylinder 4. This rests on a ring 5 secured to the lower end of the needle-cylinder 6 which is grooved longitudinally in the usual manner 25 to receive the needles 7 which have projections 8 that enter the cam-groove in the cam-cylinder. While in the present case, the cam-cylinder is shown formed with teeth 3 so it may be revolved on the needle-cylinder. 30 this movement need only be relative, and the needle-cylinder may be revolved within the cam-cylinder as in other well known machines. A radially grooved ring 10 may be secured to the needle-cylinder in any desired manner and receives the sinkers 11, 35 having heels 12, which enter the cam-groove 13 in the ring 14, which is adapted to turn on the ring 10. The needles, needle-cylinder, cam-cylinder, sinker guide-ring, sinkers, 40 and sinker cam-ring may all be of any well known construction, those shown in the drawings having been in use for many years.

Secured to the cam-cylinder by any desired means are brackets 16 and 17, the latter having a pivot-pin 18 on which the arm 19 on the ring 20 may be mounted. The other arm 21 rests on the bracket 16. A bracket 23 extends upwardly and inwardly from the arm 19 and from the ring and has 45 two downwardly projecting lugs 24 which

carry the adjustable contact screws 25. A vertical shaft 27 is adjustably secured in this bracket and carries the revolvably mounted looper-carrier 28, which has a lug 29 extending between the screws 25. This carrier supports a pin 30 on which the looper is freely revolvable, being made up of the threaded hub 31 having the flange 32, the collar 33 and the nut 34 which causes the flange and collar to rigidly hold the points 35 in proper position. It will be noticed that the looper is freely movable vertically, and freely revolvable, and that it can be removed at will without disarranging any of the other parts of the machine. Two holes, 36 and 37, in the ring, one above and the other below the points 35, permit the passage of the yarns which can be operated upon by the needles, the upper yarn being looped over the points 35 as the needle moves down. The small clips 38 serve to center the cam-ring 14 on the sinker guide-ring 10, and the lugs 39 and the adjustable contact screws 40 on the cam-ring 14 cause this ring to turn relative to the guide-ring 10 and 50 needle-cylinder 6 when engaged by the bracket 17.

The operation of this mechanism is as follows. The points 35 sustain the upper yarn against the pull of the needles sufficiently to form a loop, and as the looper-carrier turns at the same speed as the cam-cylinder, because of the engagement of the screws 40 with the bracket 17 and the engagement of the screws 25 with the lug 29, the points 35 will always enter the spaces between the needles 7, and will roll out of these spaces to disengage themselves from the loops as the carrier 28 moves along. The angular distance between the lug 29 and the screws 25, when the parts are central as in Fig. 1, may be the same as that between the bracket 17 and the screws 40, or more or less as may be desired. In any case, this distance can be predetermined accurately 55 with respect to the cam groove in the cam-cylinder 6 so that the positions of the points 35 with respect to the operative needles will always be such as may be necessary during the oscillations of the parts at the production of the heels of the hosiery.

It will be noticed that the radial distance between the pin 30 and the shaft 27 is about the extreme diameter of the looper, which gives the proper movement to the looper- 60 65 70 75 80 85 90 95 100 105 110

points 35 to freely disengage them from the loops. The width of the carrier 28 shown in Fig. 1 is desirable to hold the knitted fabric down as the points 35 are disengaging the loops. By removing the pin 18, the looping attachment can be removed and a "plain" latch-ring substituted so the product can be quickly changed from looped to smooth. This, together with the peculiar 10 novel mounting of the looper on the looper-carrier and the adjustability of the parts, provides a device which can be used with an automatic knitting machine, and will produce loops at the heels and toes of the heavy- 15 est grades of socks without requiring manual setting of the parts. When the looper is swung back, the tops for the upper ends of socks can be quickly transferred to the needles and no adjusting is necessary when the 20 looper is swung down to operative position.

I claim.

1. In a knitting machine, the combination of a needle-cylinder, needles mounted on the same, a cam-cylinder, brackets connected 25 diametrically opposite to each other to the cam-cylinder and extending upward therefrom, a ring pivoted to one bracket and resting on the other, said ring having two openings for yarns at different levels, an arm 30 mounted on said ring, a shaft extending downwardly therefrom, a looper-support freely slidable and revoluble on said shaft, and a looper revolubly mounted on said support eccentric to said shaft and having radially 35 projecting points adapted to extend between said needles.

2. In a knitting machine, the combination of a needle-cylinder, a cam-cylinder, brackets connected diametrically opposite each other on the cam-cylinder and extending 40 upward therefrom, a ring pivoted to one of said brackets and resting on the other and formed with a plurality of openings for the passage of yarns at different levels, an arm connected to said ring and a shaft rigidly mounted on the arm, and a looper-support slidably and revolubly mounted on said shaft comprising a hub and clamping members 45 slidable on said pin, and a series of points projecting radially from said clamping members, the outer edge of the looper-support extending laterally beyond the points to hold down the knitted material as the points of the looper disengage. 50

3. In a knitting machine, the combination 55 of a needle-cylinder, needles slidably mounted therein, a cam-cylinder, a shaft mounted above and concentric with the needle-cylinder, a looper-support mounted on said shaft, an upright stem on said support positioned 60 nearer to the needles than to said shaft, and a looper revolubly and slidably mounted on the stem and comprising a series of radially 65 extending points adapted to extend between said needles.

In testimony whereof I have signed this specification in the presence of two subscribing witnesses.

FRANK D. HOLMES.
